UNITED STATES PATENT OFFICE.

OTAKAR VALASEK, OF CHICAGO, ILLINOIS.

DESIGN FOR A CARD-CASE.

45,034.

Specification for Design.

Patented Dec. 9, 1913.

Application filed October 27, 1913. Serial No. 797,690. Term of patent 14 years.

To all whom it may concern:

Be it known that I, OTAKAR VALASEK, a citizen of the United States of America, residing at Chicago, in the county of Cook and State of Illinois, have invented a new, original, and ornamental Design for Card-Cases, of which the following is a specification, reference being had to the accompanying drawing, forming part thereof.

The figure is a plan view of a card case, showing my new design.

I claim:

The ornamental design for a card case, as shown.

OTAKAR VALASEK.
